E. BURHORN.
COOLING TOWER.
APPLICATION FILED SEPT. 17, 1915.

UNITED STATES PATENT OFFICE.

EDWIN BURHORN, OF HOBOKEN, NEW JERSEY.

COOLING-TOWER.

1,252,774.

Specification of Letters Patent. Patented Jan. 8, 1918.

Application filed September 17, 1915. Serial No. 51,157.

To all whom it may concern:

Be it known that I, EDWIN BURHORN, a citizen of the United States, residing at Hoboken, in the county of Hudson and State of

5 New Jersey, have invented certain new and useful Improvements in Cooling-Towers, of which the following is a specification, reference being had therein to the accompanying drawing.

10 This invention relates to cooling towers, and particularly to that class of cooling towers in which natural air currents are brought into contact with the liquid to be cooled, the latter being caused to pass by gravity 15 through the tower while subjected to the cooling influence.

The main object of the present invention is to generally and specifically improve the structure and arrangement of elements, 20 namely, the frame posts, foundation, collecting pan, etc., which are located at the lower part of the cooling tower. Other objects and advantages of this invention will appear in the hereinafter following description, and 25 further advantages will be apparent to those skilled in the art.

To the attainment of the above referred to objects and advantages, the present invention consists in the novel combinations, arrangements, devices, details and other features shown or described in the specification or drawings hereof.

I will first describe one form of cooling tower embodying the invention, and will 35 thereafter point out the novel features in the appended claims.

In the accompanying drawings, Figure 1 is a front elevation of a cooling tower embodying the present invention, with certain parts omitted for clearness and simplicity. Thus, the tower, which may be of any desired height, is shown horizontally broken off to reduce the height of the illustration. The front right-hand corner post of the 45 tower is omitted in order to show the louver arrangement along the right-hand side of the tower. The entire series of louvers at the front and rear are omitted for convenience. One corner of the collecting pan is broken 50 away.

Fig. 2 is an enlarged front elevation in detail showing the relation of the frame post, the base and the collecting pan at one corner of the tower, namely, the left-hand lower 55 corner, the illustration being partly broken away to better show the interior construction.

Fig. 3 is a top plan view, partly in section, on the plane 3—3 of Fig. 2.

Similar reference characters designate corresponding parts in the several figures.

The tower frame, which may be generally square and of any desired height, has corner posts 4, each of which is in the form of an angle iron extending vertically for the full height of the tower. Each corner post is secured within a special base casting 5, which is provided with a base flange 6 resting upon a suitable foundation. The casting 5 is hollow and the post 4 extends into its interior, 70 where the two sides of the post are securely bolted, as shown, to the corresponding sides of the base casting. The remaining space between the wall of the hollow casting and the post is filled with concrete 7, thus affording a very firm base for each post. 75

At suitable heights the corner posts 4 are connected by horizontal cross frame pieces 8 in such a way as to give a rigid unitary tower structure.

The warm water to be cooled may be supplied at the top by a distributor device 9. From here the water passes down by gravity, being stopped and held and redistributed in its downward passage by means of a series of 85 cooling decks 10 spaced apart at suitable vertical intervals. Beneath all of the decks and spaced below the lowest deck 10 is the collecting vessel or pan 11.

While it is not always necessary, I prefer 90 to provide part or all of the sides of the tower with louvers 12. These may be arranged as shown, extending generally horizontally from corner post to post, each louver consisting of a plate inclined as 95 shown. This arrangement serves to deflect the passing air currents and cause them to come more intimately into contact with the descending water. At the same time the incline of the louvers tends to prevent the loss 100 of water by blowing or splashing out of the tower. Any water falling upon a louver is preserved from loss. The louvers 12 may, for example, have generally the construction shown in my prior Patent No. 973,163, in 105 which the accumulated water is conveyed by a gutter along the bottom of each louver to the ends of the louvers so as to pass downwardly near the corner posts.

An important feature of the present construction is that the collecting pan 11 is smaller than and stands completely inside of the space inclosed by the corner posts. By this advantageous arrangement the collect-

ing pan is maintained entirely within the tower, and thus is avoided the possibility of accumulating or collecting foreign or solid matters which incidentally may be blown or 5 otherwise brought in the neighborhood of the tower. The collecting pan is, moreover, of less complicated structure and cheaper because of its smaller size.

In combination with such advantageous 10 collecting pan I have shown a special louver 13 along each of the sides of the tower at an elevation between the lowest cooling deck and the collecting pan. This special louver may be generally similar to the regular 15 louvers 12, but its inwardly inclined extremity is extended to such a degree as to overhang the edges of the collecting pan. Without this improvement a great deal of the descending water would be lost by falling 20 outside of the reduced area of the collecting pan; but this is overcome by the special louvers 13, which, it will be seen, serve to drain into the collecting pan any water which might otherwise become lost.

25 In combination with the described features I have also provided a special feature in connection with the corner posts and base casting. Thus, at a level higher than the collecting pan and at the foot of each corner post the base casting is provided or 30 formed with a collecting ledge or gutter 14. The relative arrangement of the post, the base casting and the collecting ledge is such that all water running down the posts passes 35 into the collecting ledge and from there is drained by opening 15 into one corner of the collecting pan.

It will thus be seen that an apparatus 40 has been described attaining the objects and advantages before referred to. Since many details and arrangements and other features may be indefinitely varied without affecting the principles involved, no restriction to details or features is intended, excepting as set 45 forth in the appended claims.

What is claimed is:

1. In a cooling tower of the type wherein 50 water passes downwardly by gravity and is drawn off at the bottom, the combination of an upright tower frame comprising three or more corner posts, a water distributing deck supported in elevated position by said frame, a collecting pan located at the lower end of the tower within the space inclosed 55 by said corner posts, and a collecting ledge near the base of each corner post for catching the water falling at the corners and draining it into the pan.

60 2. In a cooling tower of the type wherein water passes downwardly by gravity and is drawn off at the bottom, the combination of an upright tower frame comprising three or more corner posts, one or more cooling or

distributing decks supported in elevated position by said frame, a collecting pan located at the tower lower end within the space inclosed by said corner posts, and a hollow base casting within which each post is anchored, said base constructed with a water receiving ledge overhanging and draining 70 into the pan.

3. In a cooling tower of the type wherein 75 water passes downwardly by gravity subject to cooling by natural air currents and is drawn off at the bottom, the combination 80 of an upright tower frame comprising three or more corner posts presenting tower sides open to natural air currents, louvers across such open sides, a water distributing deck supported in elevated position by said 85 frame, a collecting pan located at the lower end of the tower within the space inclosed by said corner posts, and inwardly slanted louvers extending around the tower between said pan and deck and overhanging said 90 pan.

4. In a cooling tower of the type wherein 95 water passes downwardly by gravity subject to cooling by natural air currents and is drawn off at the bottom, the combination 100 of an upright tower frame comprising three or more corner posts presenting tower sides open to natural air currents, louvers across such open sides, a water distributing deck supported in elevated position by said 105 frame, a collecting pan located at the lower end of the tower within the space inclosed by said corner posts, means for draining into said pan descending water falling at the tower sides beyond said pan and a collecting ledge near the base of each corner post for catching the water falling at the 110 corners and draining it into the pan.

5. In a cooling tower of the type wherein 115 water passes downwardly by gravity subject to cooling by natural air currents and is drawn off at the bottom, the combination of an upright tower frame comprising three or more corner posts presenting tower sides open to natural air currents, louvers across 120 such open sides, one or more cooling or distributing decks supported in elevated position by said frame, a collecting pan located at the tower end within the space inclosed by said corner posts, and a hollow base casting within which each post is anchored, said base constructed with a water receiving ledge overhanging and draining into the 125 pan.

In testimony whereof, I have affixed my 130 signature.

EDWIN BURHORN.
